UNITED STATES PATENT OFFICE

111,688

DESIGN FOR A VEHICLE GUARD

Linus E. Russell, Springfield, Ohio, assignor to
Peters and Russell, Inc., Springfield, Ohio, a
corporation of Ohio

Application April 21, 1938, Serial No. 76,675

Term of patent 3½ years

To all whom it may concern:

Be it known that I, Linus E. Russell, a citizen of the United States, residing at Springfield, Clark County, Ohio, have invented a new, original, and ornamental Design for a Vehicle Guard, of which the following is a specification, reference being had to the accompanying drawing forming a part thereof, in which Fig. 1 is a perspective view of a vehicle guard for motor vehicles, showing my new design.

Fig. 2 is a front elevation thereof.

Fig. 3 is a side elevation.

The vehicle guard, the design of which forms the subject matter hereof, is intended to be mounted either in front of an automobile radiator and/or at the rear of the vehicle, and comprises an arch of relatively spaced, substantially parallel bars.

I claim:

The ornamental design for a vehicle guard, substantially as shown and described.

LINUS E. RUSSELL.
